(57) CLAIM

The ornamental design for a rear vehicle exterior mirror, as shown and described.

DESCRIPTION

FIG. 1 is a top plan view of a rear vehicle exterior mirror showing my new design;

FIG. 2 is a bottom plan view thereof;

FIG. 3 is a left side elevational view thereof;

FIG. 4 is a right side elevational view thereof;

FIG. 5 is a top side elevational view thereof;

FIG. 6 is a bottom side elevational view thereof;

FIG. 7 is a top perspective view thereof; and,

FIG. 8 is a bottom perspective view thereof.

The broken lines are intended to merely show the base portion of the design and is not intended to be part of the claim.
